[57] CLAIM

The ornamental design for a communication equipment enclosure, as shown and described.

DESCRIPTION

FIG. 1 is a perspective front elevation view of a communication equipment enclosure showing our new design;

FIG. 2 is a top view thereof;

FIG. 3 is a bottom view thereof;

FIG. 4 is a front elevational view thereof, which is identical to the rear elevational view except for the placement of the features along the bottom edge;

FIG. 5 is a right side view thereof; and,

FIG. 6 is a left side view thereof.
